TOWEL DISPENSING TIME-STOP
MECHANISMRudolph G. Birr, Lombard, Ill., assignor to Steiner
Sales Company, Salt Lake City, Utah, a corpo-
ration of UtahApplication April 23, 1936, Serial No. 76,040
Renewed March 17, 1938

20 Claims. (Cl. 271—2.3)

This invention relates generally to improvements in apparatus for dispensing toweling and has as a particular object to provide a simple and effective mechanism for timing an interval between toweling dispensing operations, to avoid waste. The main feature of the invention is the use of a vacuum cup as part of a timing device, which cup is caused to assume vacuum-attached relation with a suitable element, and thereafter is caused to be automatically released at the end of a timed period. Another object is to provide a simple and efficient combined stop and timing mechanism for limiting the amount of toweling dispensed at each dispensing operation and for timing an interval between dispensing operations. The invention may be applied to any type of device for dispensing toweling, either from a fabric or paper supply roll, or from a supply stack of towels, or from a supply pile of paper sheets, either folded or inter-folded. It is only necessary that some element be moved as a result of dispensing, to, in turn, control the mechanism of this invention for interrupting toweling delivery and for continuing that interruption for a predetermined time period after each toweling dispensing operation. The invention is applicable either in the hand-pull-out type of dispensing apparatus or in crank-operated or button-operated or other types. The invention includes a combined stop and timing mechanism per se, as well as a timing device per se, and the invention may be applied to any type of toweling dispensing apparatus which has an element which is moved or movable during or as a result of toweling dispensing.

Insofar as I am aware, no one has constructed a device in which a vacuum cup is caused to assume vacuum-attached relation to have its vacuum-attaching force annulled at the end of a predetermined time period.

Features include all details of construction, along with the broader ideas of means inherent in the disclosure.

Objects, features and advantages of the invention will be set forth in the description of the drawing forming a part of this application, and in said drawing

Figure 1 is a vertical transverse section of a cabinet illustrating my time-stop mechanism, and showing that mechanism in stop position and as during timing;

Figure 2 is a detail elevation partly in section, further illustrating the time-stop mechanism, looking in direction indicated by the line 2—2 of

Figure 1, and showing the parts positioned to permit dispensing; and

Figure 3 is a detail vertical section taken on line 3—3 of Figure 2.

The invention is embodied in a wall type toweling dispensing cabinet but, of course, is applicable to any type of toweling dispensing apparatus. Referring first to Figure 1: The numeral 1 designates an outer casing provided with the usual door 2. The casing has at its bottom near the rear vertical wall an elongated slot 3 upwardly through which the toweling is drawn to be connected to a soiled toweling roll 4. The toweling passes over suitable smoothing devices, 5, 6, on its way to the roll 4.

The front edge of the bottom 7 of the casing 1 is spaced from the door to provide an elongated slot 9 downwardly through which the toweling passes from a pinch roll 10. The toweling supply is indicated at 11 and the toweling passes upwardly over a feed roll 12 and between this roll and the pinch roll 10, thence downwardly. Practically the entire mechanism of the device in this instance is mounted on what I call a swing housing, capable of being swung outwardly to facilitate introduction of the fresh toweling and/or removal of soiled toweling. The housing is composed of two side plates, one of which is indicated at 15 and the feed roll 12 and the soiled toweling take-up roll 17 are, of course, journaled in the side plates 15. The rolls 12 and 17 are driven in unison at the same rate by means of a chain 18. The roll 12 has a shaft 20 which extends outwardly through the plate 15, as best shown in Figure 2.

The previously described mechanism may be of any preferred type, but is herein similar to that shown in my copending application for Towel dispensing apparatus, Serial Number 15,271. Some of the parts of the mechanism now to be described are also like that shown in the above mentioned application, and, of course, are not claimed per se herein, but are claimed in the new combination now to be described.

The invention of this application essentially comprises a combined stop and timing mechanism which is operated in this instance as a result of motion of the roll 12. Of course, the operation may be accomplished through any element which moves as a result of or during toweling dispensing.

On the end of the shaft 20 at the outer side of the plate 15 is secured an arm 25 as a stop, having at its outer end a slight projection 26 cooperable with another stop 27 which has the 55

form of a slide. This slide moves in a vertical slot 28 of side plate 15, and has an angled portion 29 which slides in a guide 30 formed between the inner side of the plate 15 and a plate 31 secured thereto, as shown in Figure 2. The slide stop 27 is provided with a lateral extension 35, and to this extension is pivoted a link 36 having a slot 37 through which passes a suitable pin 38, which is threaded into or otherwise secured to the 10 arm 25. The slide stop has a lateral extension 40 upon which is supported a vacuum cup member 41 of rubber or other suitable material. This cup is secured in this instance, as shown in Figure 3, by a screw 39. The cup proper is indicated 15 at 42 and engages, in this instance, with a stationary plate or bracket 43 to assume a vacuum-attached relation. The action of these vacuum cups is well-known, and a strong adhering action is obtained, so that the cup cannot be easily detached except by some special kind of manipulation. In this embodiment, the vacuum action is 20 annulled by gradually admitting air into what may be called the vacuum chamber defined by the cup 42 and the under surface 45 of the plate. Thus, means is provided by which the vacuum 25 action is annulled at the end of a timed period, to permit the slide 27 to fall by gravity from its position shown in Figure 1 to the position shown in Figures 2 and 3. This motion from the 30 position of Figure 1 is permitted by means of the slot 37 of the link, and it will be understood that the parts are so arranged and proportioned that the cup assumes the vacuum-attached relation of Figure 1 substantially when the pin 38 reaches its upper limit, or when it arrives at a position substantially diametrically opposite to the position shown in Figure 1. This position corresponds to about half a revolution of the shaft 20, or 35 measuring roll 12, from the position shown in Figure 2. One length of toweling is delivered for each rotation of roll 12. The downward motion of the slide 27 is limited by engagement of the upper end of slot 37 with pin 38, see Figure 2. After this setting of the cup, the arm continues 40 rotation to again assume the position shown in Figure 1, but at this time further rotation is prevented by engagement of arm 25 with slide 27 in the manner shown in Figure 1. In this instance, the cup is mounted on the slide, and although this is the preferred structure, the invention is not altogether limited thereto.

The means for annulling the vacuum holding action, in this instance (see Figure 3), includes an inlet air passage 46 in an upright element 47 mounted on plate 43. This passage is controlled by a valve 48 threaded as at 49 into the upright element 47. A suitable jam nut 50 is threaded on the upper end of the screw and engages the top of the element 47, and the screw has a screw driver slot 51. It is understood that this automatic means for annulling vacuum action may be placed differently, and it is contemplated herein to use any suitable means for the purpose of annulling this action, at the end of a time period. I intend to broadly claim the use of a vacuum cup for my purpose. By means of the screw, the time interval for release of the vacuum can be varied to suit.

When I use the expressions "vacuum cup" and "suction cup," I mean any device which can be moved toward and made to contact with any suitable surface or complementary element, and which adheres to this complementary element as a result of unequal fluid pressures acting at opposite sides of the device. It is further under-

stood that there is no intention to limit the action only to the movement of the device because either the device or its complementary element may move or both may simultaneously move towards one another.

Further, I do not intend to limit the invention to the exact location of the air inlet passage as a means for obtaining annulment of the vacuum-action for release of the cup. I do not intend to be entirely limited to the method of air introduction for this purpose because other means may be used to release the cup. However, I prefer to use the air admission scheme as the preferred scheme of obtaining release.

In order that automatic and free downward motion by gravity of the slide 27 may be assured, that is, in order to prevent detrimental frictional engagement of the arm 25 with the slide 37, after impact of the arm 25 therewith, there is provided a disk 60, see Figure 2, arranged at the 20 end of the roll 12 between the plate 15 and the roll. This disk has a peripheral shoulder 61, shown in dotted lines in Figure 1, which engages a roller 62 pivoted to the lower end of an arm 63. This arm is, in turn, pivoted at its upper 25 end as at 64 to plate 15. This engagement takes place just before the extension 26 of arm 25 engages slide 37. The arm 63 is urged in clockwise direction by spring 66 and its movement in this direction is limited by pin 67. This structure also acts as a cushioning means to reduce the shock of impact between the stops 25 and 37. After engagement of the shoulder 61 with the roller, the roller is pushed against spring action 30 in anti-clockwise direction, and then the spring acts to push the roller in clockwise direction to correspondingly cause the projection 26 to move in anti-clockwise direction to assume spaced relation relatively to the slide 27, as shown in 35 Figure 1.

The operation is as follows: The user pulls on the toweling at 53, thus rotating the roll 12 and shaft 20. The stop arm 25 rotates in clockwise direction from its position of Figure 2 (the slide 27 then being at its lowermost non-stop position) moving across the motion path of the stop 27 to the position shown in Figure 1. The arm moves through an arc of 360°, that is from the position shown in Figure 1 back to that position. The 50 slide 27 reaches its topmost position after the pin 38 has moved through an arc of 180°, and just before this arc of movement is completed the vacuum cup engages the plate to be secured thereto by vacuum action. The arm 25 then 55 completes its rotation to position the pin 38 at the bottom of the slot, thus conditioning the link and slide 27 to promptly drop when the vacuum action of the cup is annulled, to permit the arm 25 to again move in clockwise direction when 60 toweling is dispensed.

I claim as my invention:

1. A towel dispensing apparatus having means which moves as a result of towel dispensing, a first stop movable by said means, a second stop movable into the path of the first stop to limit dispensing motion of the movable means, means by which the first stop moves the second to stop position and thereafter conditions it for independent automatic motion to non-stop position, 70 a vacuum cup carried by the second stop and adapted to engage a stationary element and assume vacuum-attached relation therewith to hold the second stop against motion to non-stop position, and means by which a timed annulment 75

of said vacuum-attaching action is automatically obtained.

2. A towel dispensing apparatus having means which moves as a result of towel dispensing, a first rotatable stop movable by said means, a second stop slideable into the path of the first to limit dispensing motion of the movable means, a link by which the first stop moves the second to stop position and thereafter conditions it for independent automatic motion to non-stop position and a vacuum cup carried by the second stop and adapted to engage a stationary element and assume vacuum-attached relation therewith to hold the second stop against motion to non-stop position, and means by which a timed annulment of said vacuum-attaching action is automatically obtained.

3. In a towel dispensing apparatus having means which moves as a result of towel-dispensing, a time stop mechanism for a towel dispensing apparatus controlled by and controlling said movable means comprising, first and second independently movable stops, engageable with one another to limit dispensing motion of the movable means, means by which the first stop moves the second to stop position and thereafter conditions the second stop for independent automatic motion to non-stop position, a vacuum cup carried by the second stop and adapted to assume vacuum-attached relation with a stationary surface, to hold said second stop against motion to non-stop position, and automatically acting means by which a timed annulment of said vacuum-attaching action is obtained.

35 4. A towel dispensing apparatus having an element which moves as a result of towel dispensing, a time stop mechanism controlled by said element including a stop and means by which it is moved to stop position as said element moves as a result of towel dispensing and is thereafter released for automatic motion to non-stop position, a vacuum cup controlled by said stop to assume vacuum-attached relation with a stationary surface when the stop is moved to stop position to hold said stop in stop position, and automatically acting means by which a timed annulment of the vacuum-attaching action of the cup is obtained.

5. A towel dispensing apparatus having an element which moves as a result of towel dispensing, a time-stop mechanism controlled by and controlling said element and including a vacuum-attachable device having a vacuum cup which is caused to assume vacuum-attached relation as the element moves during dispensing to thereafter act to prevent release of the stop mechanism, and automatically acting means by which vacuum-attaching action is annulled to obtain release of the cup at the end of a timed period.

6. A towel dispensing apparatus having means which moves as a result of towel dispensing, a time stop mechanism controlled by and controlling said means, a first stop movable by said means, a second stop movable into the path of the first to limit dispensing motion of the movable means, means by which the first stop moves the second to stop position and thereafter conditions it for independent automatic motion to non-stop position, a vacuum-attachable device including a vacuum cup controlled by the second stop and adapted to assume vacuum-attached relation as said movable means moves during dispensing to thereafter hold the second stop in stopping position, and means by which vacuum-

attaching action is annulled to obtain release of the cup at the end of a timed period.

7. In a dispensing apparatus, a dispensing means, a time stop mechanism operated by and controlling the dispensing means, including a 5 vacuum attachable device having a vacuum cup which is caused to assume vacuum-attached relation to maintain stopping action of said stop mechanism, and means automatically acting to annul vacuum action of said cup to obtain release thereof at the end of a predetermined time period.

8. A towel dispensing apparatus having a time stop mechanism controlled by and controlling a measuring roll, including a vacuum-attachable 15 device, having a vacuum cup which is caused to assume vacuum-attached relation to maintain stopping action of said mechanism and means automatically acting to annul vacuum action of said cup to obtain release thereof at the end of a 20 timed period.

9. A toweling dispensing apparatus having a time stop mechanism controlled by and controlling a measuring roll including first and second stops, the second of which is disposed to promptly 25 fall by gravity to non-stop position, a pair of elements adapted when engaged to be vacuum-attached, one of said elements being connected to be moved by said second stop to become vacuum-attached as a result of motion of said stop element to stop position, means by which the measuring roll moves said stop to stop position and thereafter releases it for fall by gravity to non-stop position, and means automatically operating to annul the vacuum-attaching action to 30 permit gravity motion of the second stop to non-stop position.

10. In a dispensing apparatus, feeding means, and means preventing action of said feeding means for a predetermined time period following feeding operation of said means, said action-preventing means including separable parts which are brought together as a result of dispensing movement of said dispensing means, and are and must be held together during said timing period, one of said parts being a vacuum cup, and means by which vacuum-attaching action of said cup is automatically annulled at the end of a predetermined time period.

11. A sheet dispensing apparatus, having a stop mechanism, and a timer therefor, including elements which are brought into contacting relation as dispensing occurs and which remain in that relation during the timing period, and means for 45 automatically causing one of said timer elements to be suddenly released at the end of that period to release the stop mechanism.

12. In a sheet dispensing apparatus having a stop mechanism, a timer controlling said stop 50 mechanism, including engageable elements, means operated by dispensing for causing one of the timer elements to engage the other and means by which said elements remain engaged and immovable during timing and are suddenly automatically disengaged only at the end of timing period to release the stop mechanism.

13. A time-stop mechanism comprising two stops, one of which is movable into and out of the path of the other, a vacuum cup controlled 70 by one of the stops to assume vacuum attached and immovable relation with an immovable member when that stop is in the stopping path of the other to hold said stop also immovable, and means by which the vacuum is automatically 75

annulled at the end of a predetermined time period.

14. A sheet material dispensing device having a measuring roll, a time-stop mechanism including a pair of members adapted to be vacuum-connected when pressed together as a result of roll motion, means operated by the roll for causing said members to be pressed together to hold the stop mechanism in stop position, and means 10 automatically operable to annul vacuum action and release said members at the end of a time period to permit roll motion.

15. A sheet material dispensing device having a measuring roll, a time-stop mechanism including 15 a pair of members adapted to be vacuum-connected when pressed together as a result of roll motion, means operated by the roll for causing said members to be pressed together to hold the stop mechanism in stop position, and means 20 automatically operable to annul vacuum action and release said members at the end of a time period to permit roll motion, one of said members being adapted after release to fall by gravity to permit such motion.

25 16. A time-stop mechanism comprising two stops, the second movable into and out of the path of the first, a timer including two members, one of which is carried by the second stop to be moved by that stop into engagement with the 30 other member during movement of the second stop to stop position, means for holding said members so engaged during a time period, and means for causing the holding means to release the members at the end of a time period.

35 17. A dispensing device having dispensing means, a stop mechanism controlled by and controlling said means and including first and second stops, the second stop movable into and out of the path of the first, a timing mechanism having 40 a first part movable with the second stop, and a second part engageable by the first part as dispensing occurs and adapted to remain immovably engaged, and means to cause release of said parts at the end of a time period.

18. A dispensing cabinet having means by which the accessibility of sheet material is controlled, a timer mechanism comprising two members which become vacuum attached when brought together, means by which the vacuum is annulled at the end of a predetermined time period to obtain release of said members, means for bringing said members to vacuum attached position, and means by which one of said members controls the means for controlling the accessibility of sheet material, to so condition the same that more material is made accessible. 10

19. A dispensing cabinet for sheet material having first means which must move if sheet material is to be made accessible, and means for preventing motion of said first means for a predetermined time interval, including a vacuum-attachable member which when vacuum-attached prevents motion of the aforesaid first means, means for annulling vacuum-attaching action of 20 said member at the end of a time period, and means for moving said member to vacuum attached position, the action of said vacuum-attachable member being characterized by the fact 25 that it does not move during the time interval.

20. A dispensing roll having a first stop which rotates therewith, a second stop guided for independent linear motion and which is normally out of the path of said first stop, a pair of elements, one stationary and one carried by the second stop, one of said elements being a vacuum cup normally spaced from the other element, said elements adapted to become vacuum-attached during motion of the second stop into the path of the first stop, means carried by one of the elements for admitting air therebetween for annulling the vacuum at the end of a predetermined time period, and means by which the dispensing roll moves said second stop into the stopping path of the first stop and thereafter releases said second stop for independent movement out of the path of the first stop. 40

RUDOLPH G. BIRR.
